(57) **CLAIM**

The ornamental design for a motorcycle tire, as shown and
described.

DESCRIPTION

FIG. 1 is a perspective view of a motorcycle tire showing my
new design;

FIG. 2 is a front view thereof;

FIG. 3 is a top view thereof;

FIG. 4 is a right side view thereof;

FIG. 5 is a left side view thereof;

FIG. 6 is a fragmentary enlarged front view; and,

FIG. 7 is an end view taken along line 7-7 in FIG.6.

In the drawings, the broken lines defining the sidewall, inner
bead and the peripheral boundary between the claimed tire
tread and the unclaimed sidewall depict environmental sub-
ject matter that forms no part of the claimed design. The
light stippled surface shading represents the surface of the
tire tread, and the dark stippled surface shading represents
the recessed portion of the tread grooves, having the depth
as shown in FIG. 7.
